(57) CLAIM

The ornamental design for a combined handheld vacuum cleaner and mount, as shown and described.

DESCRIPTION

FIG. 1 is a top, rear and right-side perspective view of a combined handheld vacuum cleaner and mount showing our new design;

FIG. 2 is a front elevation view thereof;

FIG. 3 is a right side elevation view thereof;

FIG. 4 is a rear elevation view thereof;

FIG. 5 is a left-side elevation view thereof;

FIG. 6 is a top plan view thereof; and,

FIG. 7 is a bottom plan view thereof.

The broken lines are intended to show elements of the combined handheld vacuum cleaner and mount, and form no part of the claimed design.
